CLAIM

The ornamental design for a push button wall mount, as shown and described.

DESCRIPTION

FIG. 1 is a front isometric view of a push button wall mount showing my new design;

FIG. 2 is a front elevational view thereof;

FIG. 3 is a bottom plan view thereof taken along lines 3—3 of FIG. 2;

FIG. 4 is a right end elevational view thereof taken along lines 4—4 of FIG. 2, the left end elevational view being identical thereto;

FIG. 5 is a rear elevational view thereof taken along lines 5—5 of FIG. 4;

FIG. 6 is a top plan view thereof; and,

FIG. 7 is a front isometric view of the push button wall mount shown in FIGS. 1-6 with a modified front face.
